UNITED STATES PATENT OFFICE.

JAMES H. SHAFER AND THEODORE CORNUELLE, OF MADISONVILLE, OHIO.

SEPARATOR AND WASHER.

1,033,203.

Specification of Letters Patent.

Patented July 23, 1912.

Application filed September 20, 1910. Serial No. 582,840.

To all whom it may concern:

Be it known that we, JAMES H. SHAFER and THEODORE CORNUELLE, citizens of the United States, residing at Madisonville, in the county of Hamilton and State of Ohio, have invented certain new and useful Improvements in Separators and Washers, of which the following is a specification.

Our invention relates to separators and washers for material such as gravel, coal and the like.

The object of our invention is to provide a device for thoroughly sifting or washing material through a screen with the aid of water, thereby separating the coarse material from the fine and automatically discharging the coarse material from one outlet and the fine material from another outlet.

Another object of our invention is to provide a machine which may be fed rapidly in large quantities, and which automatically separates and washes the material deposited therein.

Our invention consists briefly in a receptacle, a cylindrical screen or wire mesh cylinder suspended therein and submerged partly in water, feeding mechanism communicating with said screen, means whereby said screen is rotated, an outlet for the coarse material, and mechanism whereby the fine material is withdrawn from said receptacle.

Our invention also consists in certain novel parts and combination of parts and in the details of construction as herein set forth and claimed.

In the accompanying drawings which serve to illustrate our invention: Figure 1 is a perspective view. Fig. 2 is a side elevation of same, with parts removed and the casing broken away. Fig. 3 is a rear elevation.

In the embodiment of our invention as illustrated and which shows a preferred construction, 1 represents a receptacle or tank adapted to hold water, in which the wire mesh cylindrical screen 2 is suspended. Vertical standards 3 and 4 are provided on each side of the receptacle or tank 1 and are connected at their ends by cross bars 5 and 6 on which are mounted journals 7 which are adapted to carry a driving shaft 8. Mounted on the driving shaft 8 are sheaves 9, a sprocket 10 thereon at one side of the machine and a bevel gear 11 thereon at the other end of said shaft. Horizontal bars 12 are mounted upon the cross bars 5 and 6

and are adapted to carry a shaft 13 at one end thereof which has mounted thereon a beveled gear 14 which is adapted to mesh with the beveled gear 11 on the driving shaft 8.

The wire mesh cylindrical screen 2 is provided with a frame work 2^a and end spiders or rings 15 which are provided with grooves 16 to receive chains 17; also the chains are adapted to pass around sheaves 9 mounted upon the driving shaft 8, the cylindrical screen 2 being suspended upon said chains and rotated thereby when the driving shaft 8 is operated. Mounted at some suitable place on the frame work of the receptacle 1 and journaled in journals 18 of the shaft 19 are flanged rollers 20 mounted thereon for the purpose of forming a guide and retainer for the cylindrical screen 2, thereby preventing said cylinder from wobbling and getting out of position.

A shaft 21 is mounted in the lower part of the receptacle or tank 1 at one end thereof below the cylindrical screen 2 and is provided with journals 22 mounted at some suitable point on the receptacle or tank 1. Mounted upon the shaft 21 are sprockets 23 adapted to receive a sprocket chain 24 having paddles or drags 25 thereon. An operating shaft 26 is mounted at the upper opposite end of the receptacle 1 and is also provided with sprockets 27 around which the sprocket chain 24 passes. This shaft 26 is also journaled in suitable journals 28 mounted in a suitable manner upon the receptacle 1. The chain 24 with paddles 25 thereon constitutes an endless conveyer or drag which removes the sifted material from the receptacle 1. At the end of the shaft 26 is mounted a sprocket 29 which is in alignment with the sprocket 10 mounted upon the driving shaft 8. A sprocket chain 30 connects these two sprockets 10 and 29 and thereby forms a means of driving the shafts 26 and 21.

The operation thus far is readily seen from the illustration in Fig. 1, the driving shaft 8 being rotated, operates the cylindrical screen 2 also operating the sprocket 29, which operates the conveyer or drags 25 in the proper direction, the drags forming a means of removing the sand and fine material from the receptacle 1 and pushing it up above the board 31 provided at the top of the receptacle 1.

The feeding mechanism is provided on the

side of the receptacle 1 and comprises a hopper or trough 32 having a movable notched floor 33 which is given a reciprocating motion by mechanism which will now be described. The trough 32 may be mounted as shown upon brackets 34 on the sides of the receptacle 1, and arms 35 extending therefrom to which the smaller brackets 36 are attached. A disk or crank wheel 37 is provided on and driven by the shaft 13. A rocker shaft 39 is provided below the feed trough 32 and is mounted in journals 40 on the sides of the receptacle 1. A rocker arm 41, is mounted upon said shaft at one end 10 thereof and connects to rod 38 which is eccentrically connected to the disk 37, thus imparting an oscillatory motion to the rocker arm 41 when the disk 37 is operated. Another rocker arm 42 is mounted on the shaft 39 directly under the central portion of the feed trough 32 and is connected to the movable bottom 33 of the trough 32 by means of a pitman 43. The rocker arm 42 being fastened tight to the shaft 39 operates the 15 pitman 43, thereby operating the movable bottom 33 of the feed trough 32 and imparting a reciprocating motion to the bottom of the trough 32.

The bottom 33 is provided with a groove 30 into which the sides of the trough 32 enter and thereby hold the movable bottom 33 in position during its reciprocating motion. Rollers 44 may be provided and mounted in journals 45 on the arms 35 upon which the 35 bottom 33 of the trough 32 may rest, thereby reducing the friction of the bottom 33 when it is being operated.

The trough 32 is provided with an extension 32^a which extends into the side of 40 the receptacle 1 and projects a short distance into the inside of the cylindrical screen 2, thereby insuring that all the material put into the trough 32 will eventually deposit 45 into the cylindrical screen 2. An outlet trough or chute 46 is provided at the other side of the receptacle 1 and projects into the other side of the cylindrical screen 2 through the annular opening in the ring or spider 15.

50 Mounted on the inside of the wire mesh cylinder 2 and at the end nearest the outlet chute 46 we provide a series of inwardly extending wire mesh flanges 47 which are adapted to catch the coarse material as it works itself 55 to the outlet end of the cylindrical screen 2 and carry said coarse material to the upper part or top of the cylindrical screen 2, allowing said coarse material to drop or fall out of the pockets formed between the extensions 47 into the outlet chute 46, thereby forming a means of removing said coarse material from the cylindrical screen.

A water supply pipe 48 is provided at some suitable portion of the machine which 60 65 is adapted to supply water to the receptacle

1 and is also adapted to wash the material which has been deposited into the mesh cylindrical screen 2. The outlet of the pipe 48 is preferably placed above the cylindrical screen 2 and discharges water into said cylinder, thereby washing all fine material through the wire mesh of the cylindrical screen 2 down into the receptacle 1 which is adapted to be practically filled with water. An overflow 49 is provided in the receptacle 70 75 1 near the top, thereby keeping the water in the receptacle 1 at a constant level.

The portion of the receptacle 1 which lies underneath the drag chains 24 is filled with fine sand in order to provide a soft bed for 80 the drags 25 to operate upon. The sand or fine material is constantly falling through the wire mesh screen of the cylindrical screen 2 and settling in the bottom of the receptacle 1, and is being dragged out by 85 means of the drags or paddles 25 upon the incline surface of the embankment of sand 50, as best shown in Fig. 2.

The operation of the device is as follows: The rough material such as sand or coal 90 is dumped into the feeding trough 32 and is thereby fed by means of the reciprocating movable floor in said trough gradually into the cylindrical screen 2, which being rotated gradually sifts the sand, with the help of 95 the water supply constantly flowing into the receptacle 1, through the mesh cylindrical screen 2. The coarser material remains in the cylindrical screen 2 and gradually works to the other end thereof where it enters the 100 pockets between the extending flanges of wire mesh 47 and is carried by said extensions up to the chute 46 at the upper end of the cylindrical screen 2 and is thereby deposited into the chute and carried by gravity 105 to the outside of said receptacle. While this is being done, the dragging device is constantly dragging the sand from the receptacle 1, thereby forcing it out over the edge 110 of the receptacle 1, the drags 25 being driven in the direction of the arrow shown in Fig. 2. The bed of sand 50 is provided in order to allow the paddles 25 to have a surface and yieldable bed to drag over so that a stone or hard particle which might have 115 strayed into the bed will not destroy the paddle which it engages.

This device is a positive separator which completely separates the sand from the coarse material, and by varying the mesh 120 from the smaller or inlet end of the cylinder to the larger end, the sand may be graded from very fine sand to very coarse sand.

The device is adapted not only for separating sand or coarse material but is also adapted for washing coal or separating the slack therefrom, also for removing the dirt from the slack.

Many modifications of our invention may 130

be made without departing from its spirit and scope, and we do not wish to be confined to the exact details shown.

What we claim as new and desire to secure by Letters Patent is:

1. A separator and washer comprising a receptacle adapted to contain sand and water, a revolving tapering cylindrical screen suspended partly therein, grooved rings thereon, a driving shaft above said cylindrical screen, sheaves on said shaft, endless chains extending over said sheaves and said grooved rings to suspend said cylindrical screen, means for holding said screen in proper position, said means also maintaining the chains in the sheaves, means for feeding material into said cylindrical screen and means for discharging the separated material therefrom, substantially as set forth and for the purposes specified.
2. A separator and washer comprising a receptacle adapted to contain sand and water, a tapering revolving cylindrical screen, grooved rings of equal diameter on the respective ends of said tapering revolving cylindrical screen, and arranged upon a level with each other, a driving shaft above said tapering revolving cylindrical screen, sheaves on said shaft, endless chains extending over said sheaves and said grooved rings respectively whereby said tapering revolv-

ing cylindrical screen is suspended horizontally over and partly within said receptacle and partly immersed in water, means for holding said tapering revolving cylindrical screen in proper position, both longitudinally and laterally, said means also maintaining the chains in position, means for feeding material into said tapering revolving cylindrical screen and means for discharging the separated material therefrom, substantially as set forth and for the purposes specified.

3. A separator and washer comprising a receptacle adapted to contain sand and water, a revolving tapering cylindrical screen suspended partly therein, grooved rings thereon, a driving shaft above said cylindrical screen, sheaves on said shaft, endless chains extending over said sheaves and said grooved rings to suspend said cylindrical screen, revolving flanged guides adapted to engage said grooved rings, means for feeding material into said cylindrical screen and means for discharging the separated material therefrom, substantially as set forth and for the purposes specified.
